REFRIGERATING APPARATUS

Earl D. Drake, Grand Rapids, Mich., assignor to
 Nash-Kelvinator Corporation, Detroit, Mich., a
 corporation of Maryland

Application October 16, 1941, Serial No. 415,185

3 Claims. (Cl. 220—9)

The present invention pertains to refrigerators and more particularly to refrigerator cabinet construction.

It is an object of the present invention to construct a refrigerator cabinet having inner and outer walls interconnected by relatively thin metal breaker strips of low heat conductivity extending peripherally adjacent to the opening to a food storage compartment so as to form the front wall of the cabinet and joining adjacent breaker strips by a trim strip which is held in locking engagement with the adjacent breaker strips.

It is another object of the present invention to arrange the joining of adjacent breaker strips by a trim strip so as to form an interlocking relationship therebetween.

It is still another object of the present invention to attach a trim strip in overlapping relation between adjacent breaker strips without use of screws or other external appearing affixing means.

The invention itself, however, both as to its organization and its method of operation, together with additional objects and advantages thereof, will best be understood from the following description of specific embodiments when read in conjunction with the accompanying drawing, in which:

In the drawing:

Fig. 1 is a front view of a refrigerator cabinet with parts broken away and showing features of my invention;

Fig. 2 is a fragmentary cross-sectional view taken along line 2—2 of Fig. 1;

Fig. 3 is a fragmentary rear plan view of an upper corner of the cabinet;

Fig. 4 is a perspective view of a corner trim as illustrated in Fig. 3;

Fig. 5 is a fragmentary cross-sectional view taken along line 5—5 of Fig. 3;

Fig. 6 is a fragmentary cross-sectional view taken along line 6—6 of Fig. 3;

Fig. 7 is a fragmentary rear plane view of a lower corner of the cabinet;

Fig. 8 is a perspective view of a corner trim as illustrated in Fig. 7; and

Fig. 9 is a fragmentary cross-sectional view taken along line 9—9 of Fig. 7.

Shown in the drawing is a refrigerator cabinet 20 having a food storage compartment 22. The compartment is refrigerated by a suitable refrigerating unit (not shown). An opening 24 is formed in the front wall of the cabinet for access to the food storage compartment. The opening 55

is closed by a pivotally mounted door 25 to which is secured a gasket 26 extending peripherally about the edge of the door and sealing against the front wall of the cabinet immediately adjacent to and about the opening 24 to prevent air entering the food storage compartment.

The cabinet 20 is constructed with an outer metal shell or casing 30 and an inner liner, shell or casing 32. The walls of the inner and outer shells are in spaced apart relation between which is interposed suitable heat insulation material 34. The inner shell or liner 32 forms the walls of the food storage compartment 22.

The outer metal casing 30 forms the sides and top walls of the cabinet and has its front marginal edge bent at right angles to form a portion of the front wall of the cabinet, as at 36. The portion 36 is formed with extended metal which is doubled upon the portion 36 to form the front wall of double thickness, as well as the sides and top walls a short depth from the front wall, whence the metal is bent at right angles to extend inwardly from the side walls in spaced parallel relation to the front wall, as at 37, forming pocket 40. The pocket 40 extends peripherally about the access opening 24 along the vertical sides, across the top, and is formed across the bottom in a cross member 42 which is welded to and forms an integral part of the outer casing 30.

The inner liner or shell 32 is formed with a front wall section 44 which is in substantial planar alignment with the front wall section 36 of the outer casing. The marginal edge of the section 44 is bent at right angles to form a rearwardly extending flange 46 spaced from the sides of the liner 32.

The front wall sections 36 and 44 are in substantial spaced apart relation to be joined by a heat breaker strips 50. The breaker strips are formed of relatively thin metal, preferably stainless steel or other metal having low heat conductivity, and of not greater thickness than .010 inch. The breaker strip 50 is formed to extend along a side on the front wall adjacent to the opening 24 thereof, a similar strip is positioned along the other side on the front wall, and are joined by breaker strip 51 along the top, and by breaker strip 52 along the bottom adjacent to the opening 24. Since the principle of attaching the other strips are the same, there is only shown in detail the attaching of breaker strip 50.

The breaker strip extends preferably in a convex curve from within the pocket 40 of the outer casing to over and against the face of the front wall section 44 of the inner liner. The strip is

frictionally held in the pocket by bending the marginal edge 54 to form a V with the front portion of the breaker strip. The edge 54 tensioning against the back wall 37 presses the front portion against the edge of the front wall 36. The opposite edge of the breaker strip is formed with an inwardly turned marginal edge 55 extending angularly between leg 56 of clip 57 and the front wall 44. The edge of the leg 56 is pressed upwardly, as at 58, to form a locking engagement with the edge 54.

A plurality of clips 57 are attached in spaced apart relation upon the flange 46 for the securing of the breaker strips. The clips are attached by legs 59 in flush contact against a face of the flange 46 by tongue 60 extending through an opening in the flange 46 to engage the opposite side or face of the flange 46. The leg 59 extends beyond the edge of the flange with indented portions engaging the edge which, together with the tongue 60, serve to securely affix the clip to the flange 46.

Each of the breaker strips are reinforced and stiffened by a pad 62, preferably of heat insulation material, cemented to the rear face, or the concave side of the breaker strip.

Between the vertical extending breaker strips 50 along the side adjacent to the opening 24 and the horizontally extending strip 51 along the top adjacent to the opening 24 is a spatial gap which is closed by corner trim strips 64. Each corner strip 64 extends horizontally with the top breaker strip 51 and comprises of top or cover section 65, a turned extending section 66 forming a diagonal end, and a back section 67. A tongue 70 is punched adjacent one end in section 65, and tongue 72 is punched in the back section 67. One edge of the back section is curled, as at 74.

The corner strip is attached by sliding the top section 65 horizontally with the top breaker strip 51 so as to overlap the adjacent edges of the breaker strips 51 and 50. The end of the section 65 enters the pocket 40 with the tongue 70 entering the slot 75 formed in the breaker strip 51. The slot 75 is formed elongated of sufficient length for the tongue to enter before entering the pocket, after which it is held in locking engagement by the pressure of the breaker strip towards the front wall 36 thus holding in a vise-like grip the section 65 therebetween. The opposite end of the breaker strip, the diagonal section 66, forms a diagonal corner between the breaker strips 50 and 51, while the back section 67 serves to lock the trim to the breaker strips against withdrawal. The curled edge 74 hooks over the edge 55 of the breaker strip 51, and the tongue 72 locks behind the edge 55 of the breaker strip 50. The engagement of the curled portion over an edge of the breaker strip 50 together with the tongue 70 in slot 75 serve to align the corner strip, and together with the tongue 72 engaging behind edge of strip 55 of the breaker strip 50 forms an interlocking relation between the adjacent breaker strips, and between breaker strips and corner strips. Removal of the corner strip is prevented by the tongue 72 abutting the edge of strip 50.

The opposite end of the breaker strips 50, and the adjacent ends of the bottom breaker strip 52 are cut at an angle to permit use of a diagonal corner strip 90. The strip 90 is formed with one end bent to form a U, with a back section 94 in spaced parallel relation to the top section 91 and joined thereto by connecting section 92, 78

The opposite end is formed with vertical arms 97, formed in a V, and joined with section 91. The V formed arms 97 are adapted to lie between the adjacent ends of the breaker strips 50 and 52 serving to center the top section 91 so as to lie in overlapping relation over the adjacent ends of the breaker strips. The end of the corner strip with arms 97 lies within the pocket 40. The section 92 on the opposite end serves as a diagonal corner for the adjacent joining edges of the breaker strips, with the back section 94 locking between the front wall and the turned edge 55 of each breaker strip by means of tongues 95. Each tongue 95 is held in abutment against an edge 55 of a respective breaker strip, preventing withdrawal of the corner strip.

The top sections 91 and 65 of respective corner strips 90 and 64 are formed to be in conformity to the design of the breaker strip so as to lie in snug engagement therewith, or may be formed of sufficient light weight material to readily bend and assume the contour of the breaker strip as they are attached in position. The sections 90 and 64 may if desired be embossed or impressed with designs to either stiffen or have it conform to the styling of the cabinet, or both.

By this arrangement a plurality of breaker strips are held in self-locking arrangement between the inner and outer wall by means of pocket 40 and clips 57, and interlocked together by interconnecting intermediate trim strips which also are held in self-locking engagement to the breaker strips. The arrangement being such as to facilitate assembling of the cabinet, while at the same time provides a smooth exterior front wall.

While I have shown and described the preferred form of my invention, I do not wish to limit myself to the precise detail as shown, but wish to avail myself of such variations, and modifications as may come within the scope of the appended claims.

I claim:

1. A cabinet construction comprising spaced apart wall members, a vertically extending breaker strip extending across said wall members, a horizontally extending breaker strip extending across said wall members with an end portion in close proximity to an end portion of the vertically extending breaker strip, each of said breaker strips being provided with a longitudinal turned edge portion, a relatively thin metallic member extending across the space between said end portions, means formed adjacent one end of said member to lie between the end portions of said adjacent breaker strips for alignment of said member thereover, opposite end of said metallic member extending beyond the longitudinal turned edge of said vertical and horizontal breaker strips, and means on said extended end for locking engagement with the free edge of said longitudinal turned edge portion of each of said breaker strips.

2. A cabinet construction comprising spaced apart wall members, a vertically extending breaker strip extending across said wall members, a horizontally extending breaker strip extending across said wall members with an edge portion in close proximity to an end portion of the vertically extending breaker strip, each of said breaker strips being provided with a longitudinal turned edge portion, a relatively thin metallic member bridging the space between said adjacent end and edge portions of said breaker strips, said metallic member having one end

thereof bent and extending beneath a longitudinal turned edge of said horizontally and vertically extending breaker strips, and said bent portion being provided with means engaging the free edge of said longitudinal turned edge portion of each of said breaker strips.

3. A cabinet construction comprising spaced apart wall members with vertically extending breaker strip extending across said wall members, a horizontally extending breaker strip extending across said wall members with an edge portion in close proximity to an end portion of the vertically extending breaker strip, each of said breaker strips being provided with a longi-

tudinal turned edge portion, one of said breaker strips being provided with a slot along one edge thereof, a relatively thin metallic member bridging the space between said adjacent end and edge portions and provided with means for engagement in said slot of said breaker strip, said metallic member having one end thereof bent and extending beneath a longitudinal turned edge of said horizontally and vertically extending breaker strips, and said bent portion being provided with means engaging the free edge of said longitudinal turned edge portion of each of said breaker strips.

EARL D. DRAKE.
